CAR ROOF

William D. Thompson, Detroit, Mich., assignor to
 Hutchins Car Roofing Company, Detroit, Mich.,
 a corporation of Delaware

Application January 23, 1933, Serial No. 653,205

4 Claims. (Cl. 108—5)

The invention relates to car roofs and more particularly to constructions applicable to cars of the gondola type. It is the primary object of the invention to obtain a construction which is thoroughly weatherproof and of a durable nature while at the same time providing for easy access to the interior to facilitate loading and unloading. The invention therefore consists in the construction as hereinafter set forth.

In the drawings:
 Fig. 1 is a plan view of a portion of the gondola car to which my improved roof is applied;
 Fig. 2 is a cross section thereof;
 Fig. 3 is an end elevation;
 Figs. 4 and 5 are enlarged sections on lines 4—4 and 5—5 of Fig. 1;
 Fig. 6 is a transverse section on line 6—6 of Fig. 1;
 Fig. 7 is an enlarged section on line 7—7 of Fig. 1;

Fig. 8 is a section on line 8—8 of Fig. 1;
 Fig. 9 is a section on line 9—9 of Fig. 1, and
 Fig. 10 is a section similar to Fig. 2 showing a modified construction.

Metallic cars of the gondola type as generally constructed are provided with horizontally extending reinforcing angle bars A at the top of the sides and the ends of the car. The roof frame is rigidly secured to these angle bars and comprises end members B secured to the end angles A by bolts C and tapering downward from the center to the eaves corresponding to the pitch of the roof. At the center and extending longitudinally of the car is a ridge pole D which is secured by bolts E passing through both the ends of the pole, the members B and flange of the angle A. F are carlines preferably of inverted U cross section with outwardly extending base flanges, said carlines being bolted to the angle bars A, and F' are purlines extending longitudinally of the car between adjacent carlines and bolted thereto. The angles A at the sides of the car are also provided with wooden strips G extending between adjacent carlines and secured to said angle by bolts H. These strips have their upper faces at an angle corresponding to the pitch of the roof and together with the purlines and ridge pole form a support for the roofing sheets I.

The roofing sheets I are of the usual pan shape with continuously extending up-turned flanges at their sides and across the ridge end, while at the eaves end they are provided with downturned return bent flanges J cooperating with flashings K which latter are secured between the strips G and angle bars A. The sheets I are held down

on the roof frame by transverse caps L embracing the carlines, ridge caps M and junction caps N as usual in roofs of the flexible type, while saddles O secured to the junction caps support running boards P extending from end to end of the roof. At the ends of the cars the roofing sheets I' are provided with down-turned flanges I² which are nailed or otherwise secured to end facia strips Q belted to the members B.

The roof as thus far described would form a flexible structure providing for relative movement of the sheets which are held down by the caps and would also be thoroughly weatherproofed. Inasmuch, however, as it covers the entire car there would be no provision for loading or unloading. To provide for this a number of the sheets I have hatch openings therein which are normally closed by hatch covers, the construction being as follows:

R are hatch openings cut in certain of the sheets I and S are re-inforcing channel bars which are above and riveted to the edge portions of the sheet adjacent to the openings R and surrounding said openings. To insure a weatherproof joint around the hatch openings flanges R' are turned up from the sheets I on the inner sides of the reinforcing bars S. T are hatch covers extending over and beyond the bars S being provided with downturned flanges T' at their outer edges. These covers are also preferably reinforced by ribs T² arranged on the inside thereof and riveted to the cover, said ribs extending transversely of the car within the hatch opening.

To facilitate opening and closing of the hatch covers they are hinged to the roof along the upper edges adjacent to the ridge of the roof. This hinge as shown in Fig. 9 is formed by a plate U which extends between the saddle O and the running boards P, being secured by bolts P'. At the ends of the saddle the plate U is turned downward, terminating in an eye U' which receives a shaft V, preferably of tubular form. Intermediate the saddles and the eyes U' the tubular shaft V is engaged by eyes W which are formed on plates W' riveted or otherwise secured to the upper ends of the hatch cover T. At the lower or eaves end of the hatch cover T there is arranged above the angle bar A a rock shaft X which is secured by eyes X' attached to the bolts L' which secure the transverse caps L to the angle bar A. The rock shaft X has welded or otherwise secured thereto fingers X² which extend over the lower edge portion of the hatch covers and press down thereupon to hold said

covers in position. At one end of the rock shaft X is an operating crank handle X³ which normally extends upward over one of the transverse caps L and is held down by a U-shaped clip Y attached to the cap and the carline by a bolt Y'. The clip Y has its sides apertured for the passage of a locking pin which normally extends over the crank handle X³ and holds the same in a position where the fingers X² bear downward on the hatch covers. The hatch covers are preferably provided with a bale handle Z near the eaves end thereof by means of which they may be lifted upward and turned upon the hinge rod V.

With the construction as described when the car is to be loaded the pins Y² are removed from the clips Y and the crank handles X³ turned outward to withdraw the fingers X² from the hatch covers T. These covers may then be lifted by the handle Z and thrown upward over the ridge of the roof exposing the hatch opening through which the loading or unloading may be effected. As soon as this is completed, the hatch covers are again turned down and locked in position by turning back the crank handle X³ and locking it by the pin Y².

In place of supporting the hinge rod V as above described it may be attached directly to the saddles O as shown in Fig. 10. In this construction the vertical side flanges of the saddles are perforated for the passage of the shaft V and cotter pins V² are arranged on opposite sides of the saddles to hold the shaft from longitudinal displacement. The construction is otherwise as previously described.

What I claim as my invention is:

1. In a car roof the combination with a series of roofing sheets extending from ridge to eaves, weatherproofing means for said sheets including transverse caps, ridge caps and junction caps, saddles supported upon said junction caps and running boards supported on said saddles, of a hatch cover for closing a hatch opening in one of said sheets and extending from adjacent to one side of the running board to adjacent to the eaves, a rod extending between and secured to a pair of saddles, hinge eyes for said cover engaging said rod and means adjacent to the eaves for clamping down the eaves end of said cover.

2. In a car roof the combination with a series of roofing sheets, weatherproofing means for the adjacent edges of said sheets including transverse caps, ridge caps and junction caps, saddles mounted on said junction caps, running boards supported by said saddles, a rod extending between a pair of saddles and attached thereto for clamping down the eaves and a hatch cover for closing a hatch opening in one of said sheets hinged to said rod, a rock shaft extending between and mounted upon a pair of said transverse caps at the eaves end thereof, fingers on

said rock shaft for engaging and clamping down the eaves end of said hatch cover, a crank handle for actuating said rock shaft and extending upward above one of said transverse caps and means for locking said crank handle to said cap to hold said hatch cover clamped.

3. A car roof for gondola cars having angle bar reinforcements for the upper edges of their sides and ends comprising carlines extending across said car and secured at their opposite ends to said angle bar reinforcements, a series of roofing sheets arranged between adjacent carlines and extending from ridge to eaves, weatherproofing means for said sheets comprising transverse caps embracing said carlines and the adjacent edges of the sheets on opposite sides thereof, ridge caps and junction caps, saddles mounted on said junction caps, running boards mounted on said saddles, a rod extending between and secured to a pair of said saddles, a hatch cover for closing a hatch opening in one of said sheets hinged to said rod, a rock shaft extending between adjacent transverse caps at the ridge end thereof and mounted on the means for securing said caps and carlines to said angle bars, fingers extending from said rock shaft to clamp down the eaves end of said hatch cover, a crank arm for said rock shaft extending over one of said transverse caps and a clip mounted on said cap for engaging said crank handle to normally hold the same in a position for clamping down said hatch cover.

4. In a car roof the combination with a pair of carlines, of a roofing sheet extending between said carlines and from the ridge to eaves, said sheet being provided with a hatch opening therein, reinforcing bars attached to the upper side of said sheet and surrounding said hatch opening, a hatch cover for embracing said reinforcing bars and closing the hatch opening, weatherproofing means for the edges of said sheet including transverse caps for embracing the carlines, a ridge cap and junction cap, saddles mounted on said junction caps, running boards mounted on said saddles, a rod extending between said saddles, eyes for engaging said rod having shank portions clamped between said running boards and saddles, hinge eyes on said hatch cover for pivotally engaging said rod, a rock shaft extending between transverse caps in the eaves end thereof, securing bolts for holding said transverse caps down upon said carlines, eyes in which said rock shaft is journaled attached to said securing bolts, one or more fingers on said rock shaft for engaging and clamping down the eaves end of said hatch cover, a crank arm on said rock shaft extending over one of said transverse caps and a clip for detachably holding said crank arm upon said transverse cap.

WILLIAM D. THOMPSON.
